(57) **CLAIM**

The ornamental design for a tire, as shown and described.

DESCRIPTION

FIG. 1 is a perspective view of a tire showing my new design, it being understood that the pattern repeats uniformly throughout the circumference of the tread;

FIG. 2 is a front elevational view thereof;

FIG. 3 is a right side elevational view thereof;

FIG. 4 is a left side elevational view thereof; and, FIG. 5 is an enlarged fragmentary front elevational view taken from Line 5-5 of FIG. 2.

The dashed lines represent boundary lines and form no part of the claimed design.

The interior of the tire in solid black represent environment only and form no part of the claimed design.
